(57) **CLAIM**

The ornamental design for a “brush handle,” as shown and described.

DESCRIPTION

FIG. 1 is a perspective view of a brush handle showing my new design;

FIG. 2 is a left side view thereof, the right side view being a mirror image thereof;

FIG. 3 is a top view thereof;

FIG. 4 is a bottom view thereof;

FIG. 5 is a front view thereof;

FIG. 6 is a rear view thereof;

FIG. 7 is a perspective view showing an alternative embodiment of my new design;

FIG. 8 is a left side view thereof, the right side view being a mirror image thereof;

FIG. 9 is a top view thereof;

FIG. 10 is a bottom view thereof;

FIG. 11 is a front view thereof; and,

FIG. 12 is a rear view thereof.
